UNITED STATES PATENT OFFICE.

OSCAR L. OWEN, OF WHITINSVILLE, MASSACHUSETTS, ASSIGNOR TO WHITIN MACHINE WORKS, OF WHITINSVILLE, MASSACHUSETTS, A CORPORATION OF MASSACHUSETTS.

BUNCH-BUILDER MECHANISM.

Application filed July 16, 1924. Serial No. 726,300.

To all whom it may concern:

Be it known that I, OSCAR L. OWEN, a citizen of the United States, residing at Whitinsville, in the county of Worcester and 5 Commonwealth of Massachusetts, have invented a new and useful Improvement in Bunch-Builder Mechanisms, of which the following is a specification.

This invention relates to yarn spinning 10 and winding machines of that type designed to wind yarn on a bobbin, first a preliminary winding or "bunch" and then a main winding, and the principal object of the invention is to provide a mechanism for controlling 15 the traverse of the ring rail for laying of the preliminary winding and automatic means of simple and inexpensive construction whereby the preliminary winding mechanism is rendered inoperative after the 20 "bunch" has been wound.

Another object of the invention is to provide adjustable means whereby the size and position of the "bunch" may be varied.

Another object of the invention is to provide 25 automatic means whereby the preliminary winding mechanism is set in operative position prior to the operative doffing the full bobbins from the machine.

With these objects in view, the invention 30 comprises certain novel constructions, combinations and arrangements of parts as will be hereinafter specified and claimed.

In the drawings:

Figure 1 is a front elevation of a sufficient 35 portion of a spinning machine embodying the invention to make clear its construction and manner of operation.

Figure 2 is an enlarged section on the line 2—2 of Figure 1.

Figure 3 is a detached detail showing the 40 locking latch in its inoperative position.

Figure 4 is an end elevation of Figure 3.

Figure 5 is an enlarged section of the main 45 builder cam and the preliminary winding cam on diametrical line 6—6 of Figure 2.

Figure 6 is an enlarged view of the top of the segment arm showing its relation to the locking latch actuating rod.

Figure 7 is an end elevation of Figure 6.

The invention is herein illustrated as being applied to a ring spinning machine, wherein the head or gearing end 1 is fixed to bolster rail 2 the top member of which supports a series of spindles 3 for support-

ing and rotating a series of yarn bobbins. A 55 lifter rail 4 has a series of rings 5 provided with the usual travellers, and is supported by the lifter rod 6, the lower end 7 of which being supported upon a roll 8 rotatively mounted on a stud 9 fixed to the cross shaft 60 lifter lever 10 fulcrumed at 11 in the hanger 12 fixed to the underside of the bolster rail 2. The upward traverse of the ring rail 4 is effected by the force of the weighted arm 13 imparted to the cross shaft lever 10. Extending upward from the fulcrum of the lever 10 is the segment arm 14 to which is connected one end of a chain 15 which is drawn over the sheave pulley 16 and is then 65 connected to the filling winding lever 17 working in conjunction with the builder lever 18 which is fulcrumed on the stud 19 fixed to the head end. While only a single 70 lifter lever 10 and lifter rod 6 are shown in the drawings, it is understood that any suitable number of these may be used and connected together so as to move in unison causing the ring rail to move up and down under the control of the builder motion as 75 is common and well understood in spinning and winding machines.

Mounted for rotative movement in the head end 1 is the cam shaft 20 which derives its motion from the gear 21 connected with suitable gearing to the driving shaft (not shown in the drawings) of the machine. A 80 builder motion cam 22 is fastened to the inner end of the shaft 20. The rotation of the cam acting on the follow roll 23 revolvable on a stud fixed to the builder lever 18 causes the latter to swing up and down on its pivot 19 and through connections between the builder lever and the ring rail the 85 traverse of the yarn being wound on the bobbin is effected.

The construction above described is common to spinning machines as now in use, wherein the yarn is wound on the bobbin in regular layers suitable for use in shuttles of plain looms. Where weft replenishing looms are used it is desirable that the bobbins be wound with a preliminary or "bunch" winding and then with the main winding. The "bunch" winding extends for a predetermined distance upwardly from the lower part of the bobbin, the purpose of which is to provide an engaging element to act in conjunction with the loom "feeler" mechanism 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 whereby the weft replenishing mechanism is brought into action prior to the complete exhaustion of the yarn on the bobbin in a running shuttle.

5 In order to fulfill one of the objects of my invention in winding the yarn in the form of a bunch at the lower part of the bobbin, my invention provides means whereby the ring rail is held stationary for a short 10 interval of time and then resumes its regular motion. During the retardation of the ring rail the yarn delivered is wound in form of a bunch. This effect is accomplished by means of a locking latch 24 abutting against 15 the builder lever 18 thus preventing its movements. The latch is pivoted on a stud 25 fixed in bracket 26 in stationary relation to the framing of the machine; the latch being provided with an abutment member 27 20 adjustably mounted on the lower part of the latch.

After the desired bunch is wound the latch is disconnected from its abutting engagement with the builder lever by means of a 25 cam 28 fixed to the shaft 20 and rotating in unison with the cam 22 that controls the main winding of the yarn. The cam 28 is preferably made in a disc form with one or more cam points 29 arranged on the inner 30 side of the disc. The cam point in its rotation comes in contact with a roll 30 revolvable on a stud 31 adjustably mounted on the latch 24 and thus forces the latch from its abutting relation with the builder lever.

35 In operation the operative before doffing the full bobbins and replacing with empty ones, depresses the ring rail by means of foot pressure applied to the ends of the lever 10, thus positioning the ring rail for the 40 beginning of the bottom traverse of the yarn. This action depresses the builder lever 18 to its lowest position acted thereon by the cam 22 and at the same time swings the latch 24 from its inoperative position to 45 its operative position abutting against the top of the builder lever. This is effected by suitable connections with the ring rail traversing motion, preferably I make use of a rod 32 connecting the upper arm of the latch 50 24 with the segment arm 14. The rod 32 is loosely held in a slot 33 formed in a lug 34 on the upper part of the arm 14; by this construction cramping of the rod is pre-

vented at various positions of the arm 14 due to its movements in actuating the ring rail. 55 Pressure is exerted on the rod by the lug 34 acting in conjunction with a collar 35 fixed to the rod 32. A compression spring 36 is placed on the rod between the collar and lug so as to allow an easy positioning of 60 the latch in making its abutting engagement with the builder lever.

What I claim is:

1. In a machine of the character described, the combination of a series of spindles for supporting and rotating yarn bobbins, yarn guiding means, a builder lever, a rotary cam for actuating said lever, a locking latch pivoted to a stationary part of the machine, an abutting member adjustably mounted on the locking latch and adapted to abut against the builder lever to retard its movements, a cross shaft for imparting reciprocating motion to the ring rail, an arm fixed to said shaft, a lug on the arm, a slot in the lug, a rod one end of which is slidable in said slot and the other end connected to the locking latch, a collar on the rod adjustably fixed thereto, a compression spring on the rod between the said collar and said lug, 80 a knock-off member attached to the locking latch and a cam adapted to act in conjunction with said knock-off member whereby the locking latch is released from its abutting relation with the builder lever. 85

2. In a machine of the character described, the combination of a series of spindles for supporting and rotating yarn bobbins, yarn guiding means, a builder lever, a builder cam for actuating said lever, a locking latch pivoted to a stationary part of the machine, an abutting member adjustably mounted on the locking latch adapted to abut against the builder lever to retard its movements, a knock-off cam rotating in unison with the builder cam and adapted to release the latch from its abutting relation with the builder lever, a cross-shaft actuated by the builder lever for imparting reciprocating motion to the ring rail and connecting means between the cross-shaft and locking latch whereby the locking latch is forced into an abutting relation with the builder lever. 95 100

In testimony whereof, I have signed this specification.

OSCAR L. OWEN.
